UNITED STATES PATENT OFFICE.

NELSON BLOUNT, OF JAMESTOWN, RHODE ISLAND, ASSIGNOR TO THE GOVERNMENT OF THE UNITED STATES.

TORPEDO.

Application filed July 28, 1921, Serial No. 488,214. Renewed September 24, 1924.

To all whom it may concern:

Be it known that I, NELSON BLOUNT, a citizen of the United States, residing at Jamestown, Rhode Island, have invented 5 new and useful Improvements in Torpedoes, of which the following is a specification.

This invention relates to improvements in torpedoes and more particularly to an auxiliary control of the steering mechanism. 10 In certain types of torpedoes now in use or course of development it is sometimes desirable to deflect the torpedo from its normal straight line course and the present invention is directed to a mechanism which 15 may be easily and quickly applied to torpedoes now in use for accomplishing this purpose.

One of the objects of the present invention is to provide an improved mechanism 20 adapted to be housed in a separate additional section which may be put into operation preferably by external means for causing a deflection of the torpedo either in the horizontal or vertical plane.

25 A further object is to provide a mechanism of the above character which will be of light, practical and inexpensive construction and may be readily applied to torpedoes now in general use without materially altering the same except for a slight increase in length.

Other objects will be in part obvious and in part hereinafter pointed out in connection with the attached sheet of drawings 35 forming part of this disclosure wherein,

Figure 1 is a side elevation of the auxiliary section.

Figure 2 is a central vertical section showing such parts of the mechanism as 40 are necessary to understand the invention.

Figure 3 is a sectional view taken through the forward part of Figure 2.

Figure 4 is a detail sectional view of a part of the mechanism shown in Figure 3.

45 Referring now to these drawings in detail the section shown in Figure 1 is an independent part adapted to be inserted between the war head and the forward end of the air flask. There is indicated at 1 and 2 the forward and after joint rings 50 adapted to be fitted to the head and the air flask respectively. Water tight bulkheads 3 and 4 are provided and secured to the rings 1 and 2 in any desired manner. The outer shell 5 of the section is

flush with the air flask and head exterior surfaces and slotted openings are provided for the corrective vanes hereinafter described. The mechanism with the exception of the vanes is enclosed by a ring 6 60 secured to the rings 1 and 2 in any desired manner. Vanes 7 and 8 are for correction of the course of the torpedo in a horizontal plane while vanes 9 and 10 shown in Figure 3 are for correction in a 65 vertical plane. These vanes are carried by rods 11 and 12 passing through the inner ring 6 provided with suitable stuffing boxes thence through a tube 13 in which they are free to slide within certain limits. The 70 tube 13 passes through a bracket 14 in which it is free to turn this bracket 14 being rigidly mounted on the after bulkhead 4. An arm 15 is secured to the tube 13 near its central part and between 75 the jaws of the bracket 14 as shown in Figure 2. The vane rods 11 and 12 bear against a compression spring 16 shown in Figure 4 carried on the inside of the tube 13 and each rod is provided 80 near its inner end with keys 17 and 18 adapted to slide in the respective slots cut in the wall of the tube 13 as shown in Figure 3.

These keys are adapted to transmit rotational movement of the tube 13 equally to each vane 7 and 8 through the intervening or connecting rods 11 and 12. Outward movement of the rods or keys is limited by the length of the slots which is sufficient for the vanes to clear the outer shell 5 as shown in Figure 1. The vane rods are joined together at their inner ends and limited to equal but opposite outward movement by means of the lazy tong or joint 90 construction 20 provided with a common center on the arm 15. Rotation is impressed on the unit as a whole by means of levers 21 and 22 operative by the control mechanism positioned within a casing 100 indicated at 23. This control mechanism may be of any desired type and forms no part of the present invention except either as it broadly enters into the combinations hereinafter set forth. It is preferably of 105 that type adapted to be actuated by an external source of power such as sound waves, electro-magnetic waves or the like. The vanes 7 and 8 are held in housed position against the tension of spring 16 by means 110

of a slotted sleeve 24 mounted upon the tube 13 and between a shoulder 25 on the tube 13 and the end of the key 18. This sleeve is connected by means of an arm 26 to one end of a plunger 27, Figure 2, adapted to be actuated by pressure exerted upon a copper bellows 28 against the action of an adjustably mounted spring 30.

The mechanism for actuating the vertical control vanes 9 and 10 or those for controlling the torpedo in its vertical plane is substantially the same as that above described but a showing thereof has been omitted for the sake of clearness and to avoid confusion 15 in the drawings.

In operation the torpedo is launched with the vanes in housed position as shown in Figure 2 and are held in this position by means of a locking sleeve 24. After launching, the torpedo sinks to a predetermined depth and hydrostatic pressure expands the copper bellows 28 against the action of spring 30 and rotates the sleeve 24 to bring the slot in line with the key 18 thereby releasing the vane rods 11 and 12 which are moved outwardly by the compression spring 16. The movement of these rods is limited and equal by reason of the lazy tong construction 20 the total movement being sufficient to clear the outer shell 5. In this position the vanes are free to rotate under any action impressed by means of the control 23 through the intervening levers 21 and 22 secured to the member 15.

Other methods of construction and arrangement of the parts are possible and would readily suggest themselves to one skilled in the art and I therefore do not confine myself to the specific arrangement herein shown and described which is simply for the purpose of illustrating one of various possible modifications.

It will thus be seen that the present invention is directed to a simple and practical automatic control of compact and inexpensive construction which may be easily and quickly applied to torpedoes now in general use.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention and, therefore, such adaptations should and are intended to be comprehended within the meaning and range of equivalency of the following claims.

What I claim is:—

1. In a torpedo, in combination, an auxiliary steering control section adapted to be

interposed between the air flask and the war-head, said section having rudders adapted to extend beyond the outer surface thereof. 65

2. In a torpedo, in combination, an auxiliary steering control section adapted to be interposed between the air flask and the war-head, said section being provided 70 with vertical rudders.

3. In a torpedo, in combination, an auxiliary steering control section adapted to be interposed between the air flask and the war-head, said section being provided 75 with horizontal rudders.

4. In a torpedo, in combination, an auxiliary steering control section adapted to be interposed between the air flask and the war-head, said section being provided 80 with both vertical and horizontal rudders.

5. In a torpedo, in combination, an auxiliary steering control section adapted to be interposed between the air flask and the war-head, said section having auxiliary 85 steering rudders normally housed within the section and means adapted to project said rudders outwardly from said section.

6. In a torpedo, in combination, an auxiliary steering control section adapted to be interposed between the air flask and the war-head, said section having auxiliary steering rudders normally housed within the section and means adapted to project 90 said rudders outwardly from said section, 95 said means comprising a control device operated from an external source of power and intervening means between said control device and said rudders adapted to actuate the latter. 100

7. In a torpedo, in combination, an auxiliary steering control section adapted to be interposed between the air flask and the war-head, rudders normally housed within the periphery of said section, means 105 for locking said rudders in said position, means for releasing said locking means when the torpedo is launched, means for moving said rudders outwardly from the periphery of said section and means for actuating said rudders as desired. 110

8. In a torpedo, in combination, an auxiliary steering control section adapted to be interposed between the air flask and the war-head, oppositely positioned rudders 115 normally housed within the periphery of said section, control means, means locking said rudders in housed position, hydrostatically actuated means for releasing said locking means and means for moving said 120 rudders outwardly from the periphery of said section whereby they may be operated from said control means.

Signed at Newport, Rhode Island, this 13th day of June, 1921.

NELSON BLOUNT.
